UNITED STATES PATENT OFFICE.

JOHN STIERL, OF CLEVELAND, OHIO.

GAME DEVICE.

Application filed October 20, 1926. Serial No. 142,880.

This invention relates to game devices intended especially for use in playing a game in which two sides are lined up opposite each other, with the members on one side 5 adapted to be caught or taken prisoner by members on the other side. Instead of being tagged as is common in games of this kind, the present invention contemplates the use of a catching device to engage the arm, 10 neck or body of the player caught, whereby he may be led as prisoner to the goal or other proper place.

The invention is illustrated in the accompanying drawings, in which Figure 1 shows 15 a pursued player caught with the device manipulated by a pursuing player; Fig. 2 is a plan view of the device; Fig. 3 is an enlarged sectional view on line 3-3 of Fig. 2; Fig. 4 is a sectional view on line 4-4 of 20 Fig. 3.

As shown in the drawings, the device comprises a handle 5, which may be extended to any length desired. The handle 5 has an enlarged head 6 provided with a metal 25 cap 7, slotted at the sides as at 8. A slidable bar 9 extending through the handle is secured by pins 10 and 12 in bar slots 11 and 13 respectively. A helical compression spring 14 is coiled about bar 9 in handle 30 bore 17 between pin 12 and a washer 15 and screw 16 at the rear end of the bar. A cross bar 17 riveted to bar 9 is disposed in an opening 18 in head 6 having a transverse pin 19 secured therein and extending 35 through opening 18 with a lever 20 pivoted thereon. The lever 20 is formed of sheet metal with the hand grip portion rounded and the inner folded ends 21 thereof engaging cross bar 19.

40 The forward end of bar 9 extends into an opening 22 in head 6 and has toggle links 24 pivotally riveted thereto as at 23, the links 24 pivotally connecting by rivets 25

and 26 to the crossed inner curved ends 29 and 30 of body encircling arms or bands 27 45 and 28 pivoted on a transverse pin 31 in head 6. The bands 27 and 28 are bent with a half twist 32 at the point where extending through cap slots 8 and the outer portions are formed semicircular in shape and looped 50 at the ends as at 33.

To manipulate the device for catching a player, the normally spring closed arms 27 and 28 are opened by pressing lever 20, with the fingers, thumb or palm of the hand, 55 against handle 5, the lever ends 21 moving cross bar 17 forward carrying bar 9 which straightens links 24 and turns arms 27 and 28 outwardly on pivot pin 31 as shown in dot and dash lines in Fig. 2 allowing the arms 27 and 28 to be pushed about the body 60 of the pursued player. Upon releasing the pressure on lever 20, compressed spring 14 against screw 16 forces the bar 9 rearwardly contracting links 24 and closing the arms 27 65 and 28 holding the player. The player may be released by opening the arms 27 and 28 as hereinbefore described. The bar slots 11 and 13 limit the opening and closing movements of the arms 27 and 28. 70

I claim:

A catching device comprising a handle having a slot at its front end, a bore extending rearwardly from said slot, and a recess opening from said bore through the side of the handle, a pair of crossed hooks pivoted in said slot and projecting from the front end of the handle, a spring pressed rod mounted in the bore in the handle, links in said slot between the rod and the rear ends of the hooks, and a lever mounted on the handle and extending into said recess and connected to the rod to open the hooks. 75

In testimony whereof, I do affix my signature.

JOHN STIERL.
